MIXING APPARATUS

Filed Oct. 5, 1929

INVENTOR
George H. Haines,
By Archworth Martin,
Attorney.

UNITED STATES PATENT OFFICE

GEORGE H. HAINES, OF CALEDONIA, OHIO, ASSIGNOR TO THE GRAIN MACHINERY COMPANY, OF MARION, OHIO, A CORPORATION OF OHIO

MIXING APPARATUS

Application filed October 5, 1929. Serial No. 397,513.

My invention relates to mixing apparatus, and more particularly to apparatus suitable for the mixing of feed for live stock, but it may be employed also in the mixing and conveying of other materials, and constitutes an improvement upon the disclosure of my Patent No. 1,721,553, issued July 23, 1929.

Heretofore in the use of mixers and conveyors of the vertically-disposed screw type, it has been deemed necessary to employ force feed apparatus to direct the material laterally into the conveyor conduit, or, in the case of mixers, either to provide force feed for introducing the material to the screw or to introduce the material through the top of the mixing chamber. In the case of forced feed apparatus, additional power is required, while in both instances it has been necessary to lift the bags of material in order to pour the material into the hopper of the feed apparatus or into the top of the mixing chamber.

One object of my invention is to provide an apparatus wherein the necessity for a forced feed device and for lifting the material are avoided.

Another object of my invention is to simplify and improve generally the structure and operation of conveying and mixing devices.

One form which my invention may take is shown in the accompanying drawing, wherein Figure 1 is a vertical sectional view 35 of the apparatus, and Fig. 2 is a view taken on the line II-II of Fig. 1.

In the drawing, I have shown a mixing chamber 3 having a hopper-like portion 4 and an extended cylindrical portion 5. The 40 cylindrical portion 5 is flared at its lower end to form a charging chamber 6. A shaft 7 is vertically disposed centrally of the mixing chamber 3 and extends into the conveyor or hood portion 6 of the cylindrical conduit 5. A screw conveyor is carried by the shaft 7 and has an upper portion 8 thereof disposed within the cylindrical conduit 9 that is held in place within the chamber 3 by means of brace rods 10, 11 and 12. The 45 screw conveyor has an intermediate enlarged

portion 13 disposed within a short cylinder 14 that is mounted in the conically-shaped lower end or hood 15 of the cylinder 9 and functions as set forth in my said patent.

Adjacent to its lower end, the screw is 55 enlarged as indicated at 16 to fit within the charging chamber 6 of the cylinder 5. The enlarged portion 16 of the screw is of greater diameter or radius than portions 8 and 17 thereof and is also shown as of smaller 60 pitch than the upper portions of the screw.

It has been found that if the lower end of the screw be of sufficient diameter, material will be advanced from the chamber 6 upwardly, without the necessity for forcing 65 the material into such chamber. Again, if the pitch is sufficiently small, the material will also be forced up without the necessity of the force feed. By having the lower portion 16 of the screw both sufficiently wide 70 and small enough pitch, material is advanced upwardly more effectively than if the screw were only widened in the chamber 6, or if it were of uniform diameter throughout its length and the pitch shortened in that portion lying within the chamber 75 6.

The diameter of the lower portion of the screw or its pitch, or both, will be determined by the character of material to be 80 conveyed into the mixing chamber.

The chamber 6 is preferably disposed below the floor level 18, to avoid the necessity for lifting the bags of materials which are to be introduced therein. A hopper 19 extends upwardly through the floor 11 and at its lower end communicates with the chamber 6 through the opening 20 in the wall thereof, so that material dumped into the hopper 19 will be caught by the conveyor 85 60 and elevated to the mixing chamber.

In the operation of the apparatus, sufficient material will be dumped into the hopper 19 to approximately fill the mixing chamber 3 when it is conveyed thereto by the screw, and such material will be conveyed by the portions 13 and 8 of the screw upwardly through the conduit 9 from whence it will fall into the space surrounding such conduit and pass downwardly past the hood 100 85 100

15 to be again caught by the screw and passed through the conduit 9, such circulation being maintained until the various kinds of material have been thoroughly 5 mixed as explained in my said patent, whereupon it will be drawn off through a valve-controlled spout 22 into sacks.

Further as to the utility of having that 10 portion of the screw conveyer within the charging chamber 6 of larger diameter and smaller pitch than the portion within the conduit 9, it will of course be apparent that the steeper pitch portion of the screw in the conduit 9 effects a more rapid movement 15 of the material and hence faster mixing than if the pitch were smaller. The pressure of the materials in the chamber 3 and restriction afforded by the hopper 4 around the lower end of the conduit produces pressure 20 on the material and confines it so that it will be engaged by the screw and carried up through the conduit 9 instead of being thrown off by centrifugal force.

On the other hand there is little pressure 25 of feed materials within the charging chamber 6, so that if the screw were not of sufficiently small pitch, force feed would be required in order to enable the screw to carry the material up from the chamber 6. The 30 widening of the diameter of this portion 16 of the screw compensates for the loss in effective advancing rate of the smaller pitch.

Another advantage in having the screw 35 of as great pitch as practicable throughout the major portion of its length arises from the fact that in such a screw there is less frictional losses than in the case of a screw with a greater number of turns and the wider pitch screw is less expensive to build.

40 I claim as my invention:—

1. Mixing apparatus comprising a mixing chamber, a vertical conduit in said chamber, a screw conveyer operating in said conduit, a receiving chamber surrounding the lower end of said conveyer and disposed beneath said mixing chamber and said conduit, and means for directing material in a generally downward direction into the said receiving chamber, that portion of 45 the conveyer screw within the receiving chamber being of lesser pitch than the upper portions thereof.

2. Mixing apparatus comprising a mixing chamber, a vertical conduit in said chamber, a screw conveyer operating in said conduit, a receiving chamber surrounding the lower end of said conveyer and disposed beneath said mixing chamber and said conduit, and means for directing material in 55 a generally downward direction into the said receiver chamber, that portion of the conveyer screw within the receiving chamber being of greater diameter than the upper portions thereof.

60 3. Conveying apparatus comprising a ver-

tically disposed screw conveyer, a casing surrounding said conveyer and having a side opening adjacent to its lower end, and a hopper for directing material through said opening, the conveyer screw being of relatively greater diameter adjacent to its lower end and the casing closely surrounding the screw.

4. Conveying apparatus comprising a vertically-disposed screw conveyer, a casing surrounding said conveyer and having a side opening adjacent to its lower end, and a hopper for directing material through such opening, the conveyer screw being of relatively small pitch adjacent to its lower end.

5. Conveying apparatus comprising a vertically-disposed screw conveyer, a casing surrounding said conveyer and having an opening adjacent to its lower end, and a hopper for directing material through such opening, the conveyer screw being of relatively greater diameter adjacent to its lower end, and the casing closely surrounding the screw.

6. Conveying and mixing apparatus, comprising a vertically-disposed screw conveyer, a casing surrounding the lower portion of the screw, a casing surrounding the upper portion of the screw and vertically-spaced from the lower casing, and a chamber disposed circumferentially of the second-named casing, the lower portion of the screw being of greater diameter than the upper portion thereof.

7. Conveying and mixing apparatus comprising a vertically-disposed screw conveyer, a casing surrounding the lower portion of the screw, a casing surrounding the upper portion of the screw and vertically-spaced from the lower casing, and a chamber disposed circumferentially of the second-named casing, the lower portion of the screw being of smaller pitch than the upper portion thereof.

In testimony whereof I, the said GEORGE H. HAINES, have hereunto set my hand.

GEORGE H. HAINES.
